UNITED STATES PATENT OFFICE.

FRANKLIN H. HART, OF NEW HAVEN, CONNECTICUT, ASSIGNOR TO C. COWLES & COMPANY, A CORPORATION OF CONNECTICUT.

CURTAIN ROLLER AND BRACKET.

1,378,347.

Specification of Letters Patent. Patented May 17, 1921.

Application filed January 15, 1920. Serial No. 351,606.

To all whom it may concern:

Be it known that I, FRANKLIN H. HART, a citizen of the United States, residing at 210 Howard Ave., New Haven, county of 5 New Haven, State of Connecticut, have invented an Improvement in Curtain Rollers and Brackets, of which the following is a specification.

This invention aims to produce a practical curtain or shade roller and bracket having a simplified structure with a minimum number of parts, and one which will operate in a dependable and satisfactory manner.

15 With these and other objects in view I have devised the novel curtain roller and bracket which I will now describe and hereinafter claim.

In the accompanying drawing forming a 20 part of this specification,

Figure 1 is a front elevation of the novel curtain roller and bracket, a part of the roller being broken away;

Fig. 2 an enlarged sectional view of the 25 part of the roller at the left in Fig. 1;

Fig. 3 an enlarged sectional view of the part of the roller at the right in Fig. 1;

Fig. 4 a section taken on line A—A of Fig. 2;

30 Fig. 5 a perspective view of the ratchet wheel;

Fig. 6 a perspective view of the pawl, and

Fig. 7 is a section on line 7—7 of Fig. 1.

10 and 11 are brackets supporting the 35 usual round and flat ends of the shaft 12 of the curtain or shade roller. Bracket 10 for the flat end is provided with a coil spring 10^a having at its outer end a ball 10^b which yieldingly presses against one side of

40 the flat end of the shaft, as clearly shown in Fig. 7, to prevent rattling. The roller is revoluble on the shaft and comprises a tube 13 having a cap 14 sweated to one of its ends, and a shaped disk 15 sweated to its 45 opposite end. The shaft and tube carry anti-rattling springs 13^a which have their central portions sweated to the tube and their ends encircling the shaft, as shown more clearly in Figs. 2 and 3, and on the

50 shaft is the usual coil spring. The shaft has near its flat end a boss and a washer to insure the position of the shaped disk. The shaped disk has a tubular portion 16 closely fitting the shaft and rotating thereon, and 55 an embossed portion 17 holding one end of

the coil spring. The other end of the coil spring is attached to the shaft. The shaped disk extends beyond the circumference of the tube 13, as indicated at 18, and said extending portion has lugs 19 struck up therefrom. A cap 20, having a wall 21 resting against each of the struck up lugs is fitted to said extending portion as shown at 22.

A flat disk 23 on said shaft bears against 60 said shaped disk adjacent its connection with tube 13, and between said flat disk and cap 20 is a ratchet wheel 24 having notches 25 in its outer periphery in which the struck up lugs are seated, thus holding the ratchet wheel to turn with the shaped disk and the

70 curtain carrying tube. On the inner periphery of the ratchet wheel are shoulders 26, dwells, 27, and cam surfaces 28. On the flat end of the shaft and within the ratchet wheel is arranged a pawl 29 having shoulders 30. An elongated hole 31 in the pawl allows it to slide up and down on said flat end. The pawl is provided with two shoulders so that the roller may be applied to 75 the brackets either side up.

The operation of the device will be apparent. The curtain may be drawn down against the action of the coil spring. The pawl will ride out of each dwell and up each cam surface in succession. At the end 80

85 of the downward movement of the curtain, its motion is stopped and the coil spring is allowed to slowly turn the ratchet wheel in the opposite direction until the shoulder on the pawl rests in a dwell and against a 90

shoulder on the ratchet wheel. To elevate the curtain a slight downward jerk is given it, and the coil spring is then given free action. The slight downward jerk rides the 95

pawl out of its dwell and up the adjacent cam surface, and the free action of the coil 100 spring turns the ratchet wheel rapidly. The shoulder on the pawl, not having time to seat itself by gravity in a dwell and against a shoulder on the ratchet wheel, rides down

each cam surface a portion of its distance, across each dwell and past the shoulder on its opposite side. When the curtain has 105

reached a desired elevation, the turning of the ratchet wheel is slackened by slackening the upward motion of the curtain. The pawl then seats its shoulder in a dwell and against a shoulder on the ratchet wheel. When the two shoulders are in engagement 110

the ratchet wheel is held stationary against

the action of the coil spring, as will readily be understood.

What I claim is:

1. A curtain roller comprising a pawl 5 having shoulders, a ratchet wheel, a shaped disk by which said ratchet wheel is carried, and a flat disk and a cap positioned on opposite sides of said ratchet wheel, and said pawl arranged between said flat disk and 10 cap, whereby said ratchet wheel and pawl are accurately alined so that they will positively engage each other.
2. A curtain roller comprising a shaft and a tube rotatably carried thereon, a pawl carried by said shaft, a shaped disk carried by 15 said tube and itself carrying a ratchet wheel, a flat disk arranged within the shaped disk and positioned at one side of the ratchet wheel, and a cap arranged on the other side 20 of the ratchet wheel, and said pawl positioned between said flat disk and said cap and within said ratchet wheel.
3. A curtain roller consisting of a shaft, a tube rotatably mounted thereon, and anti- 25 rattling springs which are attached to the tube and whose outer ends encircle the shaft.
4. A curtain roller and bracket, consisting of a roller comprising a shaft and tube, anti-rattling springs attached to said tube and 30 encircling said shaft, a pawl carried by said shaft and a ratchet wheel carried by said

roller, and a bracket provided with means for yieldingly holding the roller, whereby all of the parts of said roller and bracket are maintained in fixed relation to each other 35 so that positive engagement of the pawl and ratchet wheel is insured.

5. In a curtain roller a shaft, a tube rotatably carried thereon, a member rotatable on said shaft carried by said tube, a casing 40 carried by said member, a ratchet annulus detachably secured to said member within the casing, and a pawl carried by said shaft within said annulus and retained therein by the casing.

6. A curtain roller comprising a shaft, a tube rotatably carried thereon, a disk attached to said tube and journaled on said shaft, lugs on said disk, a casing carried by 45 said disk over said lugs, a ratchet wheel within the casing and having recesses engaged with said lugs, and a pawl carried by the shaft within said ratchet wheel.

7. In a curtain roller, a ratchet wheel having internal cam surfaces, dwells and 50 shoulders, a pawl having shoulders for engagement with said cam surfaces, dwells and shoulders, and disposed within said ratchet wheel, and means for accurately alining 55 said pawl and ratchet wheel.

In testimony whereof I affix my signature.

FRANKLIN H. HART.
